UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 4, 1919. Serial No. 342,341.

To all whom it may concern:

Be it known that I, CLARENCE B. FOWLER, a citizen of the United States, residing at New York, in the county of New York, State 5 of New York, have invented certain new and useful Improvements in Telephone-Exchange Systems, of which the following is a full, clear, concise, and exact description.

This invention relates to telephone exchange systems, and more particularly to such systems in which connections are to be established between telephone lines terminating at a manual exchange and telephone lines terminating at an automatic exchange.

15 The invention is especially directed, however, toward a system in which a toll operator may, in response to a call received over a calling line terminating in her position, through trunk circuits automatically 20 select the desired line terminating in an automatic exchange.

In systems of this nature it is desirable to have as little apparatus as possible connected across or in the talking conductors in 25 order to bring the speech transmission up to as high a standard as possible. Where automatic switches are utilized for connecting a calling line with a called line, it is the usual practice to have an impulse or step- 30 ping relay permanently connected to one or both of the talking conductors of the connecting circuit, which naturally reduces the speech transmission.

It is, therefore, the object of this invention 35 to provide an improved system for rapidly establishing connections between a manual or toll telephone exchange and an automatic telephone exchange, and for providing talking connections between them of 40 maximum efficiency.

In attaining the objects of this invention, an automatically selected trunk circuit, having an impulse repeating means associated therewith, is employed for extending the connections from a manual or toll to an automatic exchange, said impulse repeating means being disassociated from said trunk circuit after the connection has been established.

50 Other features which result from or are incident to the main object above noted will appear during the description of the invention.

Figs. 1 and 2, with Fig. 1 at the left, diagrammatically indicate the apparatus and

the circuits employed in carrying out the invention. Fig. 1 shows the circuit arrangement and apparatus employed at the manual exchange and Fig. 2 that at the automatic exchange.

Referring to Fig. 1 of the drawings, F represents a dialing or calling cord circuit of which there is one at each operator's position, and A a connecting cord circuit of which there are a plurality at each operator's position. Each operator has access to a plurality of trunk hunting switches C. Associated with the switchboard end of each trunk hunting switch C is a pair of jacks, one termed a connecting jack 4 and the other 60 a dialing or calling jack 1. The other end of the trunk hunting switch terminates in brushes, such as 30, 31 and 32, arranged to cooperate with terminals 34, 35 and 36 of a trunk circuit extending from the manual to 65 the automatic exchange. Normally, the dialing cord F rests in an idle dialing jack 1. When the operator desires to call a subscriber in the automatic exchange, insertion of calling cord A in the connecting jack 4, 70 causes an idle trunk to the automatic exchange, the outgoing end of which is shown in Fig. 1, to be selected.

75 Fig. 2 represents diagrammatically the incoming end of the trunk circuit and connector circuit at the automatic exchange, while E represents a subscriber's station terminating thereat. The apparatus shown to the right of the dotted line O—O is associated with the connector while that to the 80 left is associated with the incoming end of the trunk circuit.

85 Assume that the operator at the manual or toll exchange in answering a call received in the usual manner over a suitable 90 line circuit (not shown) terminating thereat, ascertains that a connection is desired with substation E on a line terminating at the automatic exchange. The insertion of plug 19 into jack 4, operates relay 14 and 95 lights lamp 17 over a circuit established from grounded battery, through the lamp 17, the resistance 18, the sleeve contacts of plug 19 and jack 4, and winding of relay 14, to ground. Upon energization of relay 100 14, all of its armatures are attracted, thus establishing circuits for relay 8 and motor magnet 10. The armatures of relay 14 are 105 so arranged that contact *a* makes before contact *b*. The circuit for relay 8 extends 110

from grounded battery, front contact and inner armature of relay 14, winding of relay 8, through the tip contacts of jack 1 and plug 20, to ground. Energization of relay 8 opens the tip and ring conductors of the trunk hunting circuit leading to the cord circuit, thus preventing the connection of ground thereto during dialing, and connects the impulse sender B to the tip and ring conductors leading to the brushes. If the switch wiper 32 is resting on a busy contact 36, ground will be present thereon. Ground will then be connected to both sides of the winding of relay 9, thus preventing its operation. Motor magnet 10 will, however, be energized over the following path: grounded battery, winding of magnet 10, armature and back contact thereof, back contact and lower inner armature of relay 9, brush 32, to grounded terminal 36. Energization of motor magnet 10 moves the brushes 30, 31 and 32 until an idle or non-grounded trunk circuit is found. As soon as an idle trunk circuit is found, relay 9 is energized over the following path: ground, front contact and middle armature of relay 14, winding of relay 9, outer armature and front contact of relay 14, back contact and armature of magnet 10, and winding thereof, to grounded battery. Motor magnet 10 is so adjusted that it will not operate in series with relay 9. Operation of relay 9 extends the tip and ring conductors of the trunk hunting circuit C through to the brushes 30 and 31, and connects ground to the brush 32. Energization of relay 9 also completes a circuit at its lower outer armature and front contact for the supervisory lamp 49 at the operator's position thus indicating that the impulses may be sent. As soon as relay 9 is operated, relay 41 is energized over the following path: grounded battery, winding of relay 41, back contact and inner armature of relay 42, terminal 34, brush 30, upper armatures and front contacts of relays 9 and 8, sleeve of jack 1, sleeve of plug 20, and the normally closed contacts 51 of impulse sender B, to ground. Energization of relay 9 closed paths simultaneously for relays 41 and 42, but relay 42 is of the slow-operating type and its circuit is interrupted at the armature and back contact of relay 41 before it is operated.

The operator actuates the impulse sender B in the usual manner to send out the impulses necessary to call the desired subscriber E. The contacts of the impulse sender B are so arranged that contact 50 is closed before contact 51 is opened, and remains closed during the sending of impulses. The first actuation of the impulse sender B closes the contact 50 to operate relay 40 over a circuit established from grounded battery, through the winding of relay 40, back contact and outer armature of relay 42, terminal 35, brush 31, upper inner armatures and front contacts of relays 9 and 8, ring of jack 1, ring of plug 20, contact 50 of sender B, to ground. Energization of relay 40, connects ground to the relay 109 of the trunk circuit at the automatic exchange causing its energization over the following path: ground, front contact and lower inner armature of relay 9, brush 32, terminal 36, alternate contacts of relay 40, front contact and armature of relay 41, resistance 45, and winding of relay 109, to grounded battery. Relay 109 attracts its armature and completes a circuit at its armature and front contact for slow-release relay 110. At each interruption of the circuit for relay 41, at the contact 51, relay 41 will be deenergized causing in turn the interruption of the circuit for relay 109 at the automatic exchange.

At the first retraction of the armature of relay 109, a circuit is completed from battery, through rotary stepping magnet 111 and the escape magnet 112 in parallel, and thence through wiper 113. A circuit is also completed from battery, through the release relay 114 to the wiper 113, the circuits being continued to ground through the front contact and armature of relay 110 and back contact and armature of relay 109. Magnet 111 and relays 112 and 114 will be energized. Relay 114 will now be held up over a circuit extending through both front contacts and the armature of relay 110, to ground through resistance 115. This resistance 115, however, is so high as not to hold up the armature of magnet 111 or relay 112. Thus, when the relay 109 next attracts its armature, the armature of rotary magnet 111 will drop back. Relay 110 being slow to release will, however, hold up during brief interruptions in its circuit at the back contact of relay 109. Thus with each interruption in the line circuit at the operator's sending device, the brushes 116, 117 and 118 of the trunk switch will be moved from one group of contacts associated therewith to the next. Any step-by-step two-movement switch may be employed with the circuits shown. A switch of this general character is shown in the Patent No. 815,176 of March 13, 1906, to Keith and Erickson. However, in the description of the present invention, the stepping magnet which first operates is described as a rotary magnet, that is, an around-and-up switch instead of an up-and-around switch shown in Keith et al. A switch of this character is shown in Patent No. 1,252,420 of January 8, 1918, to Oscar F. Forsberg. The side switch employed in the present invention may be of the type shown in the Keith et al patent or of the type similar to that disclosed in the Forsberg patent.

Resuming now the description of the op-

- eration of the circuits, when the last impulse is sent, relay 40 deenergizes, but relays 41 and 109 will remain energized, the latter due to the make-before-break contact being used on relay 40, thus holding open the circuit for the slow release relay 112 and for the rotary magnet 111. The switch brushes will be stopped in operative relation to, in the present instance, just below the group of trunk contacts desired. When the relay 112 attracted its armature, it completed a circuit for the escape magnet 119 which now retracts its armature and moves the side switch wipers to position 2. In position 2, a circuit is completed from battery, through the test relay 120, side switch wiper 121 and the normally closed contact 122. Contact 122 opens on the first vertical step. The test relay in attracting its armature, completes a circuit for the escape magnet 119. A circuit is also completed from battery, through the vertical stepping magnet 123, off-normal contact 124, wiper 125 and interrupter 126, to ground. The circuit of the vertical stepping magnet will be alternately opened and closed by the interrupter 126, causing the selector brushes 116, 117 and 118 to move from trunk to trunk of the selected group. The lower or test contact of all busy trunks will be connected to ground through resistance 115 by a circuit extending through the brush 118 and side switch wipers 121 and 113 of the selector switches associated with said busy trunks. Thus the test relay 120 will be held energized until the contacts of an idle selector are engaged. The test contact of such a selector will not be connected to ground and relay 120 will retract its armature, opening the circuit for the escape magnet 119 which in turn retracts its armature and moves the side switch to position 3. The vertical off-normal contact 124 is closed during the upward movement of the switch and opens on the tenth vertical step in order to prevent jamming of the switch in case no idle trunk is found.
- The connection from the manual or toll switchboard has now been connected to the connector switch in the automatic exchange. If desired, however, other selector switches may be interposed between the selector G and connector H.
- Assuming, however, that the present system discloses a thousands line exchange and that the series of impulses which operated the selector switch G were the hundred impulses, the operator will now operate her impulse sender to send the tens impulses, causing a series of interruptions in the circuit of relay 109 as before. With the first retraction of the armature of relay 109, circuits will be completed from battery, through the release relay 131, rotary stepping magnet 132 and the escape relay 133. The circuit for the rotary magnet 132 passes through side switch wiper 134, where it joins the lead from relay 133. The circuit is then extended through the left armature and back contact of relay 135, to the lead from relay 131, the circuit being continued through brush 118, wipers 121 and 113, front contact of relay 110 and the back contact of relay 109. Magnet 132 and relays 131 and 133 are all energized. Relay 131 will be held up by the path to ground through resistance 115 in the same manner as relay 114. Relay 133 being slow to release its armature, remains up during the series of impulses. The armature of rotary stepping magnet 132 is alternately attracted and retracted, causing the connector brushes 136, 137 and 138 to be moved from group to group of the terminal contacts of the lines terminating thereat. Upon the termination of the series of impulses, the rotary stepping magnet 132 will remain de-energized, thus stopping the switch brushes in operative relation to the tens group of contacts in which the wanted line terminates. When the armature of relay 133 was attracted, it completed a circuit from battery, through escape magnet 139 and the alternate contact and armature of relay 133, to ground, causing the energization of the escape magnet. Upon the termination of the series of impulses, relay 133 will retract its armature, opening the circuit for the escape magnet 139 and permitting the side switch to move to position 2.
- The operator will now send the last or units series of impulses. With the first de-energization of relay 109, the vertical magnet 140 and relay 133 will be energized in a manner similar to that described in connection with rotary magnet 132 and relay 133 upon sending the tens series of impulses. The brushes of the connector switch will now be stepped from line to line of the desired group until they are positioned on the contacts of the wanted subscriber's line.
- If the wanted line is already busy, the sleeve or test terminal thereof will be connected to ground through the brush 138 and wiper 141 in positions 3 and 4 of the connector switch connected thereto. If, however, the line is idle, its test terminal will be connected to battery only, through its cut-off relay 112. When relay 133 was energized due to sending the units series of impulses, the escape magnet 139 was energized in the same manner as before. Now upon the retraction of the armature of relay 133 at the end of the units series of impulses, a circuit is completed from battery, through the winding of magnet 139, the normal contacts of relay 133, test relay 135 and its right normal contact, wiper 141, and brush 138, to the test terminal of the called line.
- As soon as the impulse sender has been actuated by the operator at the manual

switchboard to send out impulses in accordance with the number of the desired subscriber, plug 20 of the dialing or calling cord is removed from jack 1 and plugged 5 into the calling or dialing jack of the next idle trunk hunting circuit, such as C. Removal of the plug 20 from jack 1 interrupts the circuit for relays 8 and 41. Relay 41, upon deenergization, completes a 10 circuit at its armature and back contact for relay 42 as follows: grounded battery, winding of relay 42, back contact and armature of relay 41, normal contact of relay 40, terminal 36, brush 32, lower inner 15 armature and front contact of relay 9, to ground. Energization of relay 42 thus disconnects the impulse repeating means associated with the trunk circuit from said trunk circuit and together with deenergization 20 of relay 8 extends the operator's telephone circuit at the manual switchboard over the talking conductors to the automatic switches at the automatic telephone exchange. Lamp 49 is also extinguished.

25 As before stated, if a called line is busy, its multiple test terminals will be connected to ground. A test relay 135 will be energized and in attracting its armature will complete a locking circuit for itself and 30 magnet 139 through its alternate contacts and the side switch wiper 151 and its second contact. Magnet 139 now being energized and the side switch being in position 2, the busy tone of device 143 will be connected to the talking circuit through the 35 left armature and front contact of escape magnet 139 and side switch wiper 144.

It will be noted that the busy tone device was connected to the upper conductor 40 of the talking circuit during the sending of the last series of impulses but as the talking circuit is not extended to the operator's telephone circuit until after the impulses have been sent and the line tested, and as the 45 side switch would be moved to position 3 simultaneously with testing of the line, the operator would not hear the busy signal if the wanted line was idle.

However, assuming that the line is busy 50 and that the operator hears the busy signal. Plug 19 is withdrawn from the jack 4. Relays 14, 8, 9 and 42 are thereupon deenergized, causing in turn the deenergization of relay 109. Relay 109, upon deenergization, 55 interrupts the circuit of relay 110 which retracts its armature, thus opening the holding circuit for relay 114 of the trunk switch and the relay 131 of the connector switch. Relay 114 in retracting its armature completes a circuit from battery, through release magnet 127, rotary off-normal contact 128 closed 60 on the first rotary step, and the armature and back contact of relay 114, to ground, thus causing the restoration of the trunk 65 switch. Relay 131 in retracting its armature,

completes a circuit from battery, through release relay 145, rotary off-normal contact 146 closed on the first rotary step, the armature and back contact of relay 131, to ground, thus causing the restoration of 70 the connector switch. It will be noted that the holding circuit for the escape magnet 139 and the test relay 135 of the connector switch is maintained until the switch is released and the side switch brushes are maintained operated until the switch is released and the side switch brushes are returned to normal, thus preventing ringing on the busy 75 lines.

Assuming now that the wanted line is 80 idle, its test connector will not be connected to ground. Thus relay 135 will not be energized and the escape magnet 139 will retract its armature moving the side switch to position 3. In position 3, a circuit is closed 85 from battery, through the escape magnet 139, the armature and contact of relay 147 and the side switch wiper 151 in its third position, to ground. The escape magnet 139 attracts its armature and completes a circuit 90 from the generator 148, through trip relay 147 and the right armature and front contact of the escape magnet 139, side switch wiper 149 in its third position, brush 137, over the right side of the subscriber's line, through the bell of the wanted subscriber's 95 substation set, back over the left side of the line, brush 136 and side switch wipers 150 and 151 and third contacts, to ground. This will cause the operation of the bell of the 100 wanted subscriber. The busy tone will not be connected to the talking conductor at this time, as the side switch is in position 3.

Upon the closing of the called subscriber's 105 switchhook, the increased flow of current through the trip relay 147 will cause it to attract its armature, thus interrupting the circuit for the escape magnet 139 and causing the side switch to move to position 4, in 110 which position the talking circuit will be established from the calling to the called line. Talking current is supplied to the called subscriber through the windings of the repeating coil in the cord circuit at the 115 manual switchboard. Busy potential will be supplied to the test contact of the called line through the side switch wipers 141 in positions 3 and 4. On completion of conversation, the operator removes plug 19 from jack 4 at the switchboard, thus causing 120 successively the deenergization of relays 14, 9 and 42 at the manual exchange, which in turn causes the deenergization of relay 109 at the automatic exchange. Relay 109, 125 upon deenergization, causes restoration of the trunk and connector switches over paths previously traced and the system is then ready for another call.

What is claimed is:

1. In a telephone exchange system, a 130

- manual telephone exchange, an automatic telephone exchange, a plurality of trunk circuits each including a pair of talking conductors and a non-talking conductor, extending between said exchanges, an impulse sending device at said manual office, means for associating said impulse sending device with an idle one of said trunk circuits, a repeater associated with said trunk circuit arranged to receive impulses from said impulse sending device over a talking conductor and to re-transmit the impulses to said automatic exchange over a non-talking conductor, and means for disassociating said repeater from said connecting circuit after said impulses have been sent. 5
2. In a telephone exchange system, a manual telephone exchange, an automatic telephone exchange, a plurality of trunk circuits for extending connections from said manual exchange to said automatic exchange, a trunk finding switch for automatically selecting an idle trunk circuit, a link circuit at the manual exchange for connection with the trunk finding switch, an impulse sender associated with the link circuit, automatic switches at the automatic exchange adapted to be controlled by said impulse sender, and means associated with said trunk circuit for repeating impulses received over a talking conductor of said trunk finding switch and said trunk to a non-talking conductor leading to said automatic exchange for controlling the automatic switches thereat. 20
3. In a telephone exchange system, a manual telephone exchange, an automatic telephone exchange, a plurality of trunk circuits including a pair of normally open talking conductors and a non-talking conductor extending between said exchanges, an impulse-sending device at said manual office, means for connecting said impulse sending device with an idle one of said trunk circuits, and a repeater connected to a talking conductor of said trunk circuit arranged to receive impulses from said impulse sending device over a talking conductor and to re-transmit the impulses to said automatic exchange over a non-talking conductor, said repeater being disconnected from said talking conductor after the impulses have been sent. 45
4. In a telephone exchange system, a manual telephone exchange, an automatic telephone exchange, a plurality of trunk circuits, each including a pair of talking conductors and a non-talking conductor, extending between said exchanges, an impulse sending device at said manual office, means for connecting said impulse sending device with an idle one of said trunk circuits, a repeater associated with a talking conductor of said trunk circuit arranged to receive impulses from said impulse sending device over a talking conductor and to re-transmit the im- 50
- pulses to said automatic exchange over a non-talking conductor, and means for disassociating said impulse repeating relay from said trunk circuit after the impulses have been sent. 70
5. In a telephone exchange system, in combination, a plurality of trunk circuits comprising a pair of talking conductors and a non-talking conductor extending between a manual exchange and an automatic exchange, a link circuit and an impulse sender at said manual exchange, a trunk finding circuit at said manual exchange, means responsive to the connection of said link circuit with said trunk finding circuit for connecting said link circuit and impulse sender with an idle trunk circuit, means for placing a busy test on the selected trunk circuit, switches at said automatic exchange adapted to operate by impulses transmitted thereto over a non-talking conductor, and means associated with said trunk circuit for repeating impulses received from said impulse sender over a non-talking conductor of said trunk circuit and for maintaining the busy test on a selected trunk during the transmission of the impulses. 75
6. In a telephone exchange system a plurality of trunk circuits each comprising a pair of talking conductors and a non-talking conductor and each terminating in a numerical switch, a link circuit terminating in a non-numerical switch, a cord circuit and an impulse sender, means operative when the cord circuit and the sender are connected to the link circuit for causing said non-numerical switch to select an idle one of the trunk circuits, means for placing a busy test on the selected trunk circuit, an impulse repeater associated with the selected trunk circuit controlled by said sender for intermittently opening the non-talking conductor of the selected trunk circuit to set the switch associated therewith, and means for maintaining the busy test on the selected trunk circuit during the operation of the sender. 90
7. In a telephone exchange system a plurality of trunk circuits each comprising a pair of talking conductors and a non-talking conductor and each terminating in a numerical switch, a link circuit terminating in a non-numerical switch, a cord circuit and an impulse sender, means operative when the cord circuit and the sender are connected to the link circuit for causing the non-numerical switch to select an idle one of the trunk circuits, means for placing a busy test on the selected trunk circuit, a relay associated with the non-talking conductor of the selected trunk circuit for controlling the setting of said switch, a circuit extending through the test contact of said non-numerical switch and including the winding of said relay, and a second relay asso- 100
- 110
- 115
- 120
- 125
- 130

ciated with the selected trunk circuit controlled by said sender for repeating impulses to said first named relay, the contacts for said second named relay interposed between the test contact of said non-numerical switch and said first named relay so that during the operation of the sender the busy test condi-

tion is maintained on the test contact of the non-numerical switch.

In witness whereof, I hereunto subscribe my name this 28th day of November A. D., 1919.

CLARENCE B. FOWLER.
